UNITED STATES PATENT OFFICE.

JOSEPH HOFFAY, OF NEW YORK, N. Y.

PHONOGRAPH CONTROL.

1,349,763.

Specification of Letters Patent. Patented Aug. 17, 1920.

Application filed June 26, 1916. Serial No. 105,908.

To all whom it may concern:

Be it known that I, JOSEPH HOFFAY, a citizen of the Republic of Mexico, and a resident of New York, in the county of New York and State of New York, have invented certain new and useful Improvements in Phonograph Controls, of which the following is a specification.

This invention relates to starting and stopping mechanisms for turntables, and particularly to mechanisms for automatically stopping the operation of a phonograph at a selected point, as for example, at the end of a record, and a general object 10 of the invention is to provide mechanism of this character which will require the setting of the mechanism for automatic stopping of the phonograph before the phonograph can be successfully operated to play a record.

In automatic stopping devices heretofore employed upon phonographs, so much manipulation has been required to set the devices for stopping the phonograph and the setting of the devices has been so uncertain, 20 that even when such devices are incorporated in phonographs, they are rarely used. In the mechanism which is the object of the present invention, the setting device is so associated with the tone arm that unless 30 the operator positions the tone arm before starting the turntable at approximately the point upon the record where he wants the playing to stop, the phonograph can not be successfully operated to effect the desired 35 playing result.

An important feature of the invention is the provision in automatic stopping mechanisms for phonographs, of an adjustable member which automatically follows the 40 tone arm when the turntable is stationary and which is operatively connected to the stopping mechanism in any tone arm position when the turntable is started or released.

My invention is fully described in the following specification, of which the accompanying drawings form a part, in which like characters refer to like parts in each 45 of the views, and in which:—

Figure 1 is a fragmentary plan view of a phonograph, partly broken away, with my device applied thereto, in position for setting the stop mechanism previous to starting the phonograph, the stylus being at approximately 50 the end of the selection on the record;

Fig. 2 is a similar view but showing the stopping mechanism bringing the phonograph to a stop when the stylus, after the rendition of the selection, has just passed 60 the point which it had occupied when the stop mechanism was set previous to starting the phonograph;

Fig. 3 is an enlarged section taken on the line 3—3 of Fig. 1, with the starting button 65 depressed after the stop mechanism has been set, and after the depression of which button the stylus has been moved manually to the beginning of the record, as indicated by dotted lines in Fig. 1; 70

Fig. 4 is a section taken on the line 4—4 of Fig. 2, after the stop mechanism has brought the phonograph to a stop;

Fig. 5 is a section taken on the line 5—5 of Fig. 2, after the phonograph has been 75 stopped;

Fig. 6 is a bottom plan view of one member of a bell-crank which I employ in the stop mechanism; and

Fig. 7 is a top plan view of the complementary member.

Referring to the drawings, 8 represents the base plate of a phonograph which carries the tone-arm 9 provided with the sound-box 10 and stylus 11 and with a trip 12, and which also carries the turntable 13 for a record 14 operable by means of the usual or any desired motor, not shown.

Arranged upon the base plate 8, beneath the turntable, is a post 15 the upper end of 90 which is braced by means of a bracket 16, said post serving as a pivot for two levers 17 and 18 held in light contact by means of coil springs 19 and 20 under normal conditions, the former bearing against the under 95 side of the bracket 16 and the latter resting upon a lever 21 vertically slidable on the post 15 and having its fulcrum in a support 22, preferably upon a knife-edge, the outer end of said lever 21 being bored for 100 the passage of a plunger 23 having a button 24 thereon and vertically movable in the base plate 8.

The lever 21 carries a pad 25 of suitable material adapted to bear against the under 105 side of the turntable 13 to serve as a brake therefor when the plunger 23 is in raised position, Fig. 4 but released from the same when said plunger is in depressed position, Fig. 3, thereby preventing or permitting 101 phonograph operation.

The plunger 23 is reduced in diameter at

26, intermediate its length, and is guided in a plate 27 shown as of triangular form, and the said plunger is passed through an elongated slot 28 in the lever 18 which is of 5 such angular formation as to be passed through and extend beneath the base plate 8 to permit this plunger connection, and said lever 18 is yieldingly held to the right, Figs. 3 and 4, by means of a spring 29 10 whereby the inner end of the slot 28 bears upon the plunger, either at its reduced portion as shown in Fig. 3, or at its normal diameter as shown in Figs. 4 and 5.

The tendency of the lever 21 is to hold 15 the plunger in raised position and to brake the turntable, Fig. 4, but if the plunger be manually depressed the brake pad releases the turntable and the reduced portion 26 moves into the horizontal plane of the lever 18, Fig. 3, and the spring 29 tends to 20 draw the lever 18 to the right to lock the plunger in such depressed position. If however, in a manner to be explained, the lever 18 is drawn to the left, by a power greater 25 than that of the spring 29, the plunger is thus released and is drawn upwardly by means of the lever 21, at which time the brake pad is again operative and the lever 18 is locked against movement toward the 30 right because of the plunger at its normal diameter.

The contacting surfaces of the levers 17 and 18 are milled, scored, abraded, or roughened, whereby said levers may move upon 35 each other when no power is applied to hold them together but, when such power is applied, said levers will be locked together and jointly form a bell-crank with the post 15 as its pivot.

40 The coil springs 19 and 20 normally hold the milled surfaces of the levers 17 and 18 together in a readily yielding manner but, when the lever 21 is swung on its fulcrum by the depression of the plunger 23, the 45 milled surfaces of the levers 17 and 18 are forced tightly together and jointly form a unit of the levers, regardless of what the relative positions of the said levers 17 and 18 had been previously. This constitutes 50 one of the essential features of my invention inasmuch as, when the plunger is raised, a spring 30 always maintains the outer end of the lever 17 against the trip 12 of the tone arm, said spring being connected with 55 the bracket 16; and I provide a stop 31 on said bracket for limiting the movement of the lever 17 to the right, Figs. 1 and 2.

With the plunger raised and the turntable locked, if the tone arm should be manually 60 carried toward the periphery of the record as indicated by dotted lines in Fig. 1, the lever 17 will rotate on the post 15 to cause the outer end thereof to bear against the trip 12 because of the spring 30, up to the 65 limit of the stop 31, and if the plunger

should at this time be depressed to start the phonograph by releasing the brake pad from the turntable the inner end of the lever 21 will rise and force the milled surfaces of the levers 17 and 18 together in a 70 relatively immovable manner with the former still bearing against the trip 12, with the result that the tone arm is prevented from feeding inwardly.

If, now, the tone arm be manually moved 75 radially outward of the record from its position at the moment of plunger depression the turntable may revolve and if the stylus be brought into record contact at any point nearer the periphery of the record so much 80 of the selection will be rendered as exists between the two points and only so much.

If the stylus be moved to approximately the end of the selection on the record, with 85 the plunger in raised position, and the plunger be then depressed to release the turntable and to lock the levers 17 and 18 together, and the stylus be then moved manually to the beginning of the selection, it follows that the tone arm may move from 90 this last named position to the end of the selection or until the lever 17 is engaged by the trip 12, the plunger being locked in depressed position up to this time. When such engagement between the trip 12 and 95 lever 17 occurs a slight additional movement of the tone arm by the record will rock the bell-crank formed by the joined levers 17 and 18, on the post 15, with enough force to overcome the power of the spring 100 29, thereby releasing the plunger from the lever 18 and permitting the spring 20 to lift the outer end of the lever 21 into braking position.

From the foregoing, it will be seen that 105 the stylus must always be in the position where it is desired that the record shall be stopped before the plunger is depressed to start the phonograph and that the stylus must thereafter be moved to the portion of 110 the selection whereat it is desired that rendition shall begin, and that only such portion of the selection as occurs between these two points will be rendered, whether it be the entire selection or only a desired portion thereof, or whether it be an entire selection utilizing the entire record or a short selection utilizing only a portion of the record.

Further, while I have shown a satisfactory detailed structure, it will be understood 120 that I am not limited thereto but may make changes thereover, provided that such changes do not depart from the spirit of the invention nor fall outside of the scope of 125 the appended claims.

Having fully described my invention, what I claim as new, and desire to secure by Letters Patent, is:—

1. The combination with a turntable and 130

a member traveling thereover as said turntable rotates, of mechanism for automatically stopping the rotation of said turntable after a selected movement of said member thereover, said mechanism comprising an element arranged to follow the movements of said member when the turntable is at rest, and means for automatically locking said element in any position into which it has been moved by said member when said mechanism is rendered inoperative to permit the turntable to rotate, thereby to set said mechanism for the selected movement.

2. In a phonograph, the combination with a turntable and a member traveling thereover as said turn-table rotates, of adjustable mechanism for automatically stopping the rotation of said turn-table after a predetermined movement of said member thereover, said mechanism comprising an adjustable trip and means for automatically locking said trip in any selected adjustment upon the release of said turn-table.

3. The combination with a turntable, a traveling member and brake mechanism, of adjustable means for effecting the actuation of said brake mechanism when said means is engaged by said traveling member, and connections between said means and said mechanism operating to lock said means in adjusted position upon the release of said brake mechanism.

4. The combination with a turntable, a traveling member and brake mechanism, of movable means for holding said brake mechanism in released position, an arm normally adjustable relatively to said holding means and arranged to be engaged by said traveling member, and means for automatically locking said arm to said holding means as said brake is released.

5. In a phonograph, the combination with a turntable, a member traveling over said turn-table, and brake mechanism, of means for holding said brake mechanism in released position, and a brake actuating trip movable with said traveling member when said turn-table is stationary and means for automatically locking said trip to said holding means, upon the release of said brake mechanism, in any position into which it has been moved by said traveling member.

6. In a phonograph, the combination with a turntable, a tone arm traveling thereover as said turntable rotates, and a brake, of means for actuating said brake to stop the turntable, comprising a member in the path of and free to follow the movements of the tone arm when the brake is set, and means automatically operated when the brake is released for effecting an operative connection of said member to the other elements of the brake actuating means in any tone arm position.

65 7. In a phonograph, the combination with

a power-driven turntable, and a tone arm traveling thereover as said turntable rotates, of means for stopping said turntable, comprising a member in the path of and free to follow the movement of the tone arm when the turntable is in stopped position, and means operating automatically as said turntable is again brought under the control of its power drive to effect an operative connection between said member and the other elements of the stopping means in any tone arm position.

8. In a phonograph, the combination with a turntable, a tone arm traveling thereover as said turntable rotates, and turntable stopping means, of means for automatically tripping said stopping means, comprising two members, one of which is arranged to move at all times with the tone arm and the other of which is arranged to follow the movement of the first when the stopping means is operative and to be operatively connected to said stopping means when the stopping means is in inoperative position, and means whereby the movement of the stopping means into inoperative position automatically effects such operative connection in any tone arm position.

9. As an article of manufacture, for use on a phonograph, a support, a post, two levers pivoted on said post in normally independent relationship and provided with roughened contacting surfaces, a plunger, a lever in operative connection therewith and with said post, and a brake on said lever for said phonograph, depression of said plunger moving the respective end of said last named lever downwardly and the other end upwardly to force the roughened surfaces of said first named levers into binding contact to prevent relative movement of said levers.

10. As an article of manufacture, for use on a phonograph, a support, a post, two levers pivoted on said post in normally independent relationship and provided with roughened contacting surfaces, springs for maintaining said levers in contacting relationship, a plunger, a lever in operative connection therewith and with said post beneath one of said springs and a brake on said last named lever for said phonograph, the actuation of said plunger depressing said brake and compressing said springs to force said first named levers into immovable relationship.

11. As an article of manufacture, for use on a phonograph, a support, a post, two levers pivoted on said post in normally independent relationship and provided with roughened contacting surfaces, a spring normally holding one of said levers yielding against rotation on said post, a plunger, a lever in operative connection therewith and with said post, and a brake on said

last named lever, depression of said plunger lowering said brake and forcing said first named levers into relatively immovable relationship.

5. 12. As an article of manufacture, for use on a phonograph, a support, a post, two levers pivoted on said post in normally independent relationship, one of said levers being provided with an elongated slot at its 10 outer end, a plunger passed through said slot, and provided with a shoulder normally above said slot, a spring for drawing said lever into locking engagement with said shoulder when said plunger is depressed to 15 prevent upward movement of said plunger, a lever in operative connection with said plunger and with said post, and a brake on said last named lever, depression of said plunger lowering said brake and forcing 20 said first named levers into relatively immovable engagement.

13. In a phonograph, the combination with a power-driven turntable, a member traveling thereover as said turntable rotates, and mechanism for controlling the starting and stopping of said turntable, of 25 a lever having one arm relatively adjustable to the other about its fulcrum and ar-

ranged to be moved by and to follow the movement of said member when the turntable is stationary, the other arm of said lever being connected to said mechanism to govern the turntable stopping action of said mechanism, and means operating automatically as said controlling mechanism is 35 moved into turntable starting position for locking said lever arms together. 30

14. In a phonograph, the combination with a power-driven turntable, a tone arm traveling thereover as said turntable rotates, and mechanism for controlling the starting and stopping of said turntable, of a lever having one arm connected to said mechanism to govern the stopping action thereof and having its other arm free to 40 move relatively to said first arm about the lever fulcrum, when said turntable control mechanism is operative to maintain said turntable stationary, and also arranged to be moved by and to follow the movements 45 of said tone arm, and means connected to said control mechanism and operated by the movement thereof into starting position for locking said lever arms together. 45

JOSEPH HOFFAY.
